UNITED STATES PATENT OFFICE.

KINNEY I. MILLER, OF LANCASTER, MISSOURI.

REENFORCED LID FOR CHICK BOXES.

Application filed July 10, 1926. Serial No. 121,588.

This invention relates to an improved form of reenforced pasteboard lid or cover for boxes or crates designed for shipping or transporting baby chicks, or the like, and to a method of making such cover. These boxes are ordinarily made of heavy pasteboard, and are provided with the usual flanged lids, through which are cut a plurality of ventilating apertures. Wooden slats or cleats are ordinarily nailed across the outer sides of the lids, both for strengthening the structure and to space the boxes from each other when they are piled up together in a car, so as to allow the air to circulate to some extent amongst the live chicks. But these wooden cleats are rather expensive, they require time for nailing onto the lids, and their added weight causes a further expense in the way of postage or express charges.

It is the purpose of the present invention, therefore, to provide a form of pasteboard lid for an ordinary pasteboard box such as is commonly employed for shipping chicks, which lid shall include integrally formed strengthening ribs or bosses, pressed from the pasteboard stock of which the lid is constructed; and which ribs, while serving every required purpose of the said wooden cleats, can be so incorporated in the structure of the lid at a much less first cost, and will also reduce postage or other transportation charges through their lessened weight.

In the drawings

Figure 1 is a plan view of a blank sheet of pasteboard stock as required for making up a lid, the portions intended to form the side flanges and transverse strengthening ribs being indicated by dotted lines;

Figure 2 is a plan view of the same sheet, showing the angular or V-shaped strengthening ribs pressed up across the entire sheet, the intended side flanges being indicated in dotted lines;

Figure 3 is a detail of a strip of the reinforcing tape, which in the preferable structure is to be pasted along and over the gaps of the V-shaped strengthening ribs at the under side of the completed lid;

Figure 4 is a plan view of the reverse side of the structure as shown in Figure 2, showing the tape represented in Figure 3 pasted along and over the gaps of the V-shaped ribs, at the intended under side of the lid;

Figure 5 is a top plan view of the completed lid;

Figure 6 is a side elevation of a box equipped with this improved lid;

Figure 7 is a detail showing the method of forming the V-shaped strengthening ribs in a piece of pasteboard stock;

Figure 8 is a detail showing the application of the reinforcing tape across the gap of a rib, at the under side of the lid.

In carrying out this invention, I take a blank sheet 1 of pasteboard stock, or any other suitably pliable material, adaptable to form a lid 2 for the box 3, and in any conventional manner I press and form across the said sheet, and integrally with the sheet, two or more spaced strengthening ribs 4, which may be angular or V-shaped in cross section, as here shown, or of any other desired shape. These ribs 4 are formed to protrude at that side of the sheet 1 which is intended to serve as the upper or outer side of the completed lid 2. Strips of reinforcing tape 5 are next pasted along over the gaps 6 of the V-shaped ribs 4, at the intended under side of the lid. Incisions 7 are then made transversely through the ribs 4 at points registering with the lines 8 which mark the juncture of the side flanges 9 of the lid 2 with the body of the lid.

The side flanges 9 are then turned perpendicularly down, and the ends of these flanges are bound or locked together in any conventional manner to form the corners 10. The usual ventilation apertures 11 may be formed in the lid. Boxes equipped with lids formed and made in the manner pointed out, may be stacked upon one another without danger of the ribs 4 crushing, and these ribs thus serve as a substitute for the usual wooden cleats. The portions of the same ribs protruding laterally as shown at 12 prevent the boxes being crowded too closely together, and thus spaces are left at all sides of the assembled boxes for the free circulation of air.

Where boxes are to be shipped singly, or only a few at a time, so that the danger of their crushing together is comparatively slight, the reinforcing strips or tape 5 may be dispensed with, and the lids may be made with the angular ribs 4 alone. Lids can be very cheaply constructed after this method, and will serve every purpose for which the more costly wooden cleated boxes are in-

tended, while their use also results in materially lessened transportation charges.

It is evident also that this form of box or crate may be useful for shipping other commodities or perishable food-stuffs, or whenever a cheap, light and strong box is required, or when it may be desirable to stack such boxes and at the same time provide for air spaces between the same.

10 While I have herein described a certain order and manner of carrying out my said method of constructing the said lid for the character of box referred to, and have described the said lid as being built and assembled in a certain way, it is understood that I may depart and vary from the said method pointed out, and may construct the said box with minor variations from the structure shown, not departing, however,

from the spirit of the invention as laid down in the appended claims.

I claim:

1. A box lid of pliable material provided with integral, outwardly directed strengthening bosses, and reenforcing tape secured over the gaps of the said bosses.

2. In combination with a box lid of pliable material and having integral side flanges, outwardly directed bosses formed integrally with the lid across the body and side flanges thereof, and reenforcing tape secured over the gaps of the said bosses.

3. A box structure having integrally formed bosses outstanding at one side of the structure, and reenforcing tape secured over the gaps of the said bosses.

In testimony whereof I affix my signature.

KINNEY I. MILLER.
